MULTIPLE ACTION INTERVAL TIMER

Raymond D. Smith, Pleasantville, N. Y., assignor,
by mesne assignments, to Tremont Products
Corporation, Boston, Mass., a corporation of
Massachusetts

Application February 2, 1923, Serial No. 616,549

30 Claims. (Cl. 200—39)

This invention relates to timer mechanism involving a slow-moving, time-giving means such as a clock movement and particularly in which the clock or other slow moving mechanism is inactive except during the period when the controlled device, such as a gas valve or electric switch, is subject to timer control. Such kind of timer mechanism I prefer to designate as an interval timer rather than a "time switch" or "time valve", the latter being terms commonly employed to designate time-controlled mechanism of a kind in which the clock is continuously running, usually for a week, and wound up only after it has well "run down".

15 Among the particular problems solved by my present invention is the provision of simpler and cheaper time control for enabling an electric switch, gas valve, or other occasionally used agent, to be tensioned by hand actuation for two or more 20 automatic successive functions to take place at respectively different times as governed by the time mechanism after the latter is set in action.

By the present invention I accomplish this, in the case of an ordinary rotary snap switch, by 25 making use, for effecting the automatic time-controlled functions, of the same switch operating spring which in the ordinary switch acts to cause the snap action of the switch contacts responsive to hand actuation of the switch control button. 30 I am thereby relieved of the expense and complication of providing an additional switch-actuating motive means as has heretofore been employed in time switches and a consequent decrease results in the cost and number of parts employed.

35 The present invention provides a single time movement with appropriate control means or timer hands constituting a common means for accomplishing all of the following functions:— for winding the "main" or driving spring of the 40 movement, for indicating the time for which the clock will run and the time at which the switch will be automatically actuated thereby and also for operating the contacts directly by hand if desired without waiting for the set time to elapse 45 so that by establishing respectively different settings of a plurality of the said timer hands, the automatic actions of the switch can be predetermined as to time and manual or non-automatic actions effected. A store-keeper may thus set 50 my improved interval timer to perform the double action of turning his window lights "on", say, at 8 o'clock, and "off" again at 11 by one setting of the device, or a house-wife may cause the current for the heating oven of her electric range 55 to come on at 3 o'clock in the afternoon and go

off at 5 o'clock for cooking the evening meal while she is absent. Through suitable circuit connections the double circuit controlling action of this switch may operate, first, to reduce and then to extinguish the controlled lighting circuit for uses in the poultry business where it is desired to have a period of reduced light before darkness to give time for the fowl to find their roost. 60

The invention will be better understood by reference to the following description in connection with the accompanying drawings and its scope is particularly pointed out in the appended claims. 65

In the drawings, Fig. 1 is a front view of the interval timer with casing, switch button, and 70 timer hands removed, and certain parts broken away.

Fig. 2 is a side view looking at the right of Fig. 1 showing the casing and parts of the control hands, certain parts being shown in central vertical section and other parts being broken away to better show the construction as hereinafter described.

Fig. 3 is a view of the switch detent mechanism taken on plane 3—3 in Fig. 2 looking in direction of the arrow. 80

Fig. 4 is a view of the pawl and ratchet controlling inter-relation of the timing cams and is taken in section on the plane 4—4 in Fig. 2.

Fig. 5 shows the switch and timer levers as positioned when switch is in "on" position and not tensioned for time-controlled action. 85

Fig. 6 is a view like Fig. 3 with position of parts corresponding to position of switch in Fig. 5.

Fig. 7 is a view of the lock members for switch 90 operating shaft taken in section on plane 7—7 in Fig. 2, parts being positioned to correspond with Fig. 5.

Fig. 8 shows the position of timer cams when the timer hands point at zero and corresponding 95 to the position of switch shown in Fig. 5.

Fig. 9 shows the switch in "on" position tensioned for timer controlled escapement to "off" position.

Fig. 10 is similar to Fig. 3, position of parts 100 corresponding to Fig. 9.

Fig. 11 is similar to Fig. 7, position of parts corresponding to Fig. 9.

Fig. 12 is similar to Fig. 8 showing the timer cam that controls escapement of switch for 105 movement to "off" position rotated so that slot in same is removed from register with timer lever and switch thereby held under tension in "on" position as shown in Fig. 9.

Fig. 13 shows switch held in "off" position by 110

timer lever and tensioned for double automatic action at respectively different times.

Fig. 14 is a view similar to Fig. 3, position of parts corresponding to Fig. 13.

5 Fig. 15 is a view similar to Fig. 7, position of parts corresponding to Fig. 13.

Fig. 16 is a view similar to Fig. 8, both timer cams being rotated to position for locking the timer levers.

10 Fig. 17 is a front view of the timer casing with switch button in "on" position, both timer hands pointing to zero corresponding to relation of mechanical parts shown in Figs. 5 to 8 inclusive.

Fig. 18 is a view similar to Fig. 17 showing 15 switch in "on" position but tensioned for automatic escapement to "off" position when the "off" timer hand returns to zero, the corresponding position of mechanical parts being as in Figs. 9 to 12 inclusive.

20 Fig. 19 is a similar view showing the switch in "off" position but tensioned for a double escapement, first to "on" and then to "off" position, the position of mechanical parts being as shown in Figs. 13 to 16 inclusive.

25 Fig. 20 shows in front view, corresponding to Fig. 1, a modified construction for effecting clock control of the timer levers.

Fig. 21 shows the parts of Fig. 20 in locking position.

30 Fig. 22 is a plan view partly in section, looking down on Fig. 20.

Fig. 23 shows a further possible form of the clock-controlled, lever-locking device.

35 Fig. 24 shows a construction whereby the time-indicating dial is carried by and in adjustable relation to the timer handle for certain useful purposes.

Fig. 25 is a view partly in section looking at the right of Fig. 24.

40 Fig. 26 shows a concentric instead of adjacent relation of the "on" and "off" timer handles and dials.

Fig. 27 is a view looking up at Fig. 26 and is taken partly in central horizontal section.

45 Fig. 28 shows a special form of switch dial to indicate when the switch is cocked for automatic action.

50 Fig. 29 is a view similar to Fig. 1 showing the timing mechanism of my present improvement connected to operate a valve such as shown in my United States Patent No. 1,385,098, issued July 19, 1921, part of the mechanism being taken in section on the plane 29—29 of Fig. 30 looking in the direction of the arrows.

55 Fig. 30 is a view taken partially in section on the plane 30—30 in Fig. 29 looking in the direction of the arrows.

60 Fig. 31 is a fragmentary sectional view taken on a vertical plane through the center of spindle 35 in Fig. 1 looking from the right and showing the frictional mounting of ratchet wheel 39.

In the drawings the same symbol designates the same part throughout the different views.

65 There are three main systems of mechanism in my improved interval timer; one, a rotary snap switch, which may be single or double pole or of any desired circuit-controlling arrangement and shown in the drawings as carried by the insulating base 10 of porcelain or suitable material, and secured by screws 11 to the frame 12; the second system embodies a clock escapement mechanism mounted in frame plates 13 secured to the frame 12; and the third system consists of various rotative parts including the "on" timer lever 14 and the "off" timer lever 15 which are

pivoted by a bearing bolt 16 to a bearing standard 17 projecting from the frame 12.

First, I will describe the mechanical parts of each of the three above systems and then describe how they function in my improved interval timer.

The porcelain base 10 of the snap switch carries on opposite sides thereof interconnected plates 18—18a which serve as bearings for the switch shaft 19, this shaft by means of flats on same at different points along its length, fixedly carrying a spring anchorage 20, cam 21 for operating the link 30 and a shaft-locking member 22.

The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

90 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

95 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

100 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

105 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

110 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

115 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

120 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

125 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

130 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

135 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

140 as retaining and snap-release detent, to control the follow-up movement of the barrel 26 relative to the shaft 19 by successive engagements and disengagements with the four teeth 31 on plate 18 (see Fig. 3). The switch mechanism thus far described operates on a principle common to most rotary snap switches with minor variations of construction and I have added to such ordinary construction only the member 22 co-operating with pawl 32 at the base of the switch for holding the switch shaft 19 rotatively advanced thereby to manually establish the tension for effecting time controlled automatic, follow-up action of the contact blades 25 relative to the shaft 19.

145 The contacts of the switch comprise stationary spring clips 23 carried by two binding posts 24, for attachment of leading-in wires not shown;—one of which clips and binding posts is indicated by dotted lines in Fig. 2 because falsely positioned to accord with Fig. 1 and there is a rotating blade structure comprising contact blades 25 mounted in insulated relation on the rotating barrel 26 with one end of which the switch operating spring 27 engages; the other end of this spring engaging the shaft anchorage 20 and being thereby rotated with the shaft 19. At the base of the barrel 26 is fixedly carried a plate 28 having two downward projections 29, the space between same serving as guide for the projecting arm of the link 30 which as moved radially by cam 21 and rotatively by the projections 29 acts,

in a clock-wise direction without corresponding movement of the gear 37, because of slippage between ratchet wheel 39 and spindle 35. But this friction is strong enough to permit the 5 tarding train to restrain the action of main spring 36 in the usual running of the clock.

On the spindle 35 I fixedly mounted cam 40 which is to control the "Off" action timer lever 15 by position of its peripheral slot 40a and on the 10 hub 40b of cam 40 I loosely mount a similar cam 41 to control the "On" action timer lever 14 by position of its peripheral slot 41a and retained by the thrust collar 70. For the purpose of enabling cam 40 to drive cam 41 positively in a clock-wise 15 direction while permitting cam 41 to be adjusted to different rotative positions relative to cam 40 in either relative direction, I employ a pawl 42 pivoted to cam 41 at 42a and co-acting with a ratchet wheel 43 fixed to the hub of cam 40, 20 this pawl 42 having a projecting arm 44 protruding through an opening 44a in cam 41 and adapted for engagement by whatever manual operating instrumentality is provided for adjusting the rotative setting of cam 41 in its different 25 rotative positions. In the structure as shown, this operating instrumentality for cam 41 is the "On" timer hand 45 which acts on cam 41 through the medium of gear 46 on which it is mounted by means of a bracket 46a, pinion 47, and gear 30 48, the latter having a slot 49 engaging the projection 44 of pawl 42 and thereby acting on suitable occasions to release pawl 42 from its locking engagement with ratchet wheel 43. The cam 40 is operated directly by timer hand 50 which is 35 fixed to the end of its hub.

There remains to be described the pivot construction of the timer levers 14 and 15 and the gear 46. The head of pivot stud 16, when the latter is tightly set, clamps firmly against the 40 bearing standard 17, the following members,—bearing collar 51 of greater thickness than timer lever 15, stop bracket 53 for timer lever 15, spacer collar 55, stop bracket 54 for timer lever 14, bearing collar 51 of greater thickness than timer 45 lever 14, pinion bracket 56, and bearing collar 52 of greater thickness than gear 46. A rigid mounting of parts 51, 53, 55, 54, 51a, 56 and 52 is thereby secured while permitting entire rotative freedom of timer levers 14 and 15 and gear 46.

50 The pinion bracket 56 is further located and held in position through engagement with the front frame plate 13 of the clock mechanism and carries a pivot stud 57 for pinion 47.

The spring 58 loosely coiled around the spacer 55 collar 55 acts on levers 14 and 15 to urge the former counter-clockwise into the path of arms 33 and out of engagement with the slot 41a, and to urge the lever 15 clockwise and into the path 60 of arms 33 and out of engagement with slot 40a.

Before "setting" for automatic action the normal position of the switch-operating button and timer hands are as shown in Fig. 17 where both timer hands point to zero on their respective dials 45a and 50a and the switch may be in either 65 "on" or "off" position. To indicate whether "on" or "off" I may mount the usual form of switch indicator dial 60 omitted from Figs. 1 to 19 inclusive to rotate with the arms 33 whereby the words "on" or "off" come to register with an 70 opening 61 through the casing as is well understood in the art, and, therefore, the construction not herewith shown in detail.

Starting with the controls positioned as in Fig. 17, at which time the mechanism is positioned as in Figs. 5 to 8, it is apparent that suc-

cessive turning of the switch button to the right will cause the switch to alternately snap "off" and "on" in the usual way without interference by the clock as timer levers 14 and 15 are then free to recede from the path of travel of the 80 ends of arms 33 by dipping into slots 40a and 41a in cams 40 and 41, respectively, which cams are normally at rest in a position wherein said slots register with the ends of said detent levers, the spring 58 being weak enough to permit this yielding of levers 14 and 15, and the pivotal and angular relation of levers 14 and 15 being such with respect to the path of travel of arms 33, that the latter may thrust the former out of their path in passing.

If, as in Fig. 17, the switch is in the "on" position and it is desired to set it to automatically snap to "off" position (to break the circuit) at a predetermined time, the "off" timer hand 50 is turned to the left an amount corresponding to the desired time interval and then the switch button is turned to the right until it is felt to latch and hold. The arms 33 are prevented from following up the switch shaft 19 because the slot 40a in cam 40 has been removed from register 95 with timer lever 15 and the latter is locked in the path of arm 33 to restrain it as shown in Fig. 9. When so restrained the preponderance of the thrust of arm 33 against lever 15 is taken by the pivot bolt 16 and only a small component of this 100 thrust is transmitted as pressure on the cam 41. Also the switch shaft 19 is caught and held in its rotatively advanced position by this action of pawl 32 and member 22, thus establishing tension in the switch-operating spring 27, tending 105 to move the blades 25 to break the circuit. This movement of the blades cannot occur, however, until arms 33 are released by the timer lever 15, which takes place when the clock, which begins to run as soon as timer hand 50 is removed from 110 zero, has returned timer hand 50 to zero position and slot 40a to position permitting the dipping of detent lever 15 thereinto. From reference to Fig. 10, it will be seen that in the "set" or "cocked" position of the switch parts the link 30 is positioned radially out of engagement with the stationary tooth 31 on plate 18 by the relative movement which has taken place between the cam 21 and the plate 28 as the latter is held back and the former advanced and that on time-controlled 115 escapement of the arms 33 rotation of the link 30 with plate 18 while the cam 21 is still held stationary, will retract the link radially so that it engages with the next tooth 31 of plate 18 and assumes its usual function of stopping the switch 120 blades 25, in their circuit-breaking position. So long as the timer hands 45 and 50 remain at zero it will be understood that this spring and link arrangement functions in the usual way to cause 125 a quick make and break action of the switch as operated by hand turning of the button 34.

If, as in Fig. 19, the switch is in the "off" position, and it is desired to set it to automatically snap first "on" and then "off" at respectively different and predetermined times, then both the 130 "off" and "on" timer hands are turned to the left an amount corresponding to the respective desired intervals and, as before, the switch button is turned to the right until it is felt to latch and hold. In this case, the arms 33 are first prevented from following up the switch shaft 19 by interception of timer lever 14 because the slot 135 41a in cam 41 has been removed from register with the end of same.

The clock now starts to run and rotates cam 150

40 and the ratchet wheel 43 in clockwise direction (Fig. 16). Through the engagement of pawl 42 with ratchet wheel 43, the cam 41, to which pawl 42 is pivoted, is rotated in unison with cam 5 40 and therefore through the medium of gear 48, pinion 47 and gear 46, the "on" action timer hand 45 is rotated back to zero in unison with "off" action timer hand 50, on their respectively different centers. When the "on" action timer 10 hand 45 reaches zero, slot 41a in cam 41 comes to register with detent lever 14 and arms 33 are permitted to escape and the switch snaps to the "on" position and "makes" the circuit. Before this escapement parts are positioned as shown 15 in Figs. 13, 14, 15 and 16. After this first escapement parts are left positioned as in Figs. 9, 10, 11 and 12 and thereby under control of the "off" action timer which proceeds, as has heretofore been fully described, to operate as in the 20 case of the single escapement action. Attention is called to the performance of link 30 during this double automatic escapement. Before the first escapement it was positioned as in Fig. 14. Keeping in mind that the switch shaft 19, and, 25 consequently the cam 21, remains stationary during all time-controlled automatic actions of the switch, it will be seen that in traveling from the position in Fig. 14 to position in Fig. 10, the link 30 travels first outwardly a little way and then 30 begins to return inwardly, but does not return far enough to interfere with the next tooth 31 on star plate 18, so that the switch is left free for its second automatic escapement to "off" position when released by the detent lever 15. Obviously, a gear and rack or any of the well-known 35 forms of rotary snap switch spring and detent construction could be substituted for the link 30 and cam 21.

40 Returning now to the mechanism by which the cam 40 positively impels cam 41 in a clockwise direction, but is released from the connection by which it so impels said cam when the latter is positioned at zero, it is seen from reference to Fig. 4, that when the pawl 42 is driven against the stationary pinion bracket 56 the latter acts 45 as a stop and the former is swung on its pivot to release from engagement with ratchet wheel 43, after which the cam 41 is stopped from further clockwise travel because pawl 42 is limited in its swing, but the cam 40 is freely permitted so to 50 continue its travel to zero where it is stopped by engagement of its stop lug 62 with a projection 63 on the casing. Another lug 64 on cam 40 engages with lug 65 on cam 41 to limit the possible time settings of latter to positions rotatively 55 intermediate that of cam 40 and "zero" position. In other words, the "on" action timer hand 45 cannot be set to consume a greater interval of time in its return to zero than can the "off" 60 action timer hand 50. The stops 62, 63, 64 and 65, imposing these limitations of travel on cams 40 and 41 have been shown on the drawings where they could be pictured most clearly without regard to preferred construction as would be employed in practice.

65 Referring further to the inter-operative relation of cam 40 and cam 41 it will be seen that with the "off" action timer hand 50 positioned, say, as in Fig. 19, the "on" action timer hand 70 45 is free for setting to any position intermediate that of the hand 50 and zero, for the reason that the natural yielding of pawl 42 permits independent clockwise turning of hand 45 and the 75 unlocking pressure of gear 48 against pawl 42 releases the pawl from engagement with ratchet

wheel 39 to also permit independent counter-clockwise turning of hand 45 within the limits above described, when turned by its designed operating hand 45.

The U-shaped spring 66 is anchored in a hole 67 in gear 48 and passing through an elongated slot 68 in said gear is anchored at its other end in a hole 69 in cam 41 for the purpose of preventing any pressure of gear 48 on pawl 42 tending to unlock same when the clock is driving both cams in their "set" rotative relation back to zero position. This spring, however, permits the small amount of lost motion between gear 48 and cam 41 by which the pawl 42 is manually unlocked for time-setting.

90 Although, as a simple embodiment, the escapement-controlling detent mechanism in Figs. 1 and 2 is shown as consisting of the simple two pivoted timer levers 14 and 15 bearing directly on the clock-driven cams 40 and 41 during the entire timing interval whereby the switch arms 33 are restrained from action, I may, within the scope of this invention, relieve the clock cams from even this continual slight pressure of timer levers 14 or 15 during running of the clock, by 95 separately mounting shiftable lock members to lock and unlock levers 14 and 15, as, for example, the pivoted cams 71 and 72 in Fig. 20.

Two independent bracket supports 73 and 74 are provided with pivot screws 75 and 76 giving preferably a frictional mounting by means of which lock cams 71 and 72, while shiftable, by the clock for locking and unlocking levers 14 and 15 retain such position as they are left in. Taking the place of cams 40 and 41, I may provide the revolving pins 77 and 78, respectively, having the same driving relation to each other and to the clock spindle 35 as have cams 40 and 41. Fig. 20 shows the unlocked position of cams 71 and 72 and Fig. 21 shows the locking position. The pins 77 and 78 may pass cams 71 and 72 in either direction of rotation actuating them in one direction to locking position and by passing in the opposite direction, to unlocking position. Many schemes of timer action are made possible by this principle and will suggest themselves to those skilled in this art as entirely within a mechanic's 100 skill and requiring no further exercise of invention as, for instance, the use of members 71 and 72 and of members 71a and 72a or of the movement thereof to in other ways affect or cause 105 movements of switch contacts for circuit controlling action, and the clock-driven parts, as before described, are subjected to no pressure by the thrust of the switch arms 33 when the switch is cocked.

110 In Fig. 23 is shown a modified form of lock members corresponding to cams 71 and 72 in Figs. 20, 21 and 22, whereby the springs 79 and 80 normally urge the cams 71a and 72a into locking positions, but yield to the pressure of pins 77 and 78, when the latter are driven against same by the clock. The stop pins 81 and 82 limit the swing of cams 71 and 72 so that the latter may act as a positive stop for pins 77 and 78 in positions of the latter corresponding to zero positions of the timer hands 45 and 50.

115 Referring to Figs. 24 and 25, in the practical use of an interval timer it is often the case that the user habitually sets the timer to act at a certain hour of the day and as the time-indicating dials in Figs. 17, 18 and 19 serve only to indicate intervals of time that will elapse before the automatic switch action, it becomes necessary for the user to each day mentally compute the elapsed 120 125 130 135 140 145 150

time for which he must set the switch, knowing the time of day at which he sets it and the time of day he wishes it to act. I am aware that it is an old expedient to make a dial with time-indicating graduations rotatively adjustable on the casing as a means for mechanically computing the elapsed time and obviously any of the time dials herein shown as stationary such as 45a and 50a could be so made rotatively adjustable if desired as in the case of dial 86a in Figs. 26 and 27 which latter dial projects from the casing to be rotatable relative thereto, but I believe it new with this invention to provide such a time-indicating dial carried by, and rotatively adjustable 10 in relation to, the time-indicating and setting handle, by which certain important advantages are derived. Assuming, for instance, that it is the user's habit to set the action for 2 o'clock each day, he will adjust the time-graduated ring 83 20 in Fig. 24 so that the pointer on the setting hand points at 2 o'clock. Then at whatever time of day he happens to cock the timer for action, he has but to turn the pointer on 84 and therewith the ring 83 until the stationary arrow 85 registers 25 with the actual time of day, no interval of time requiring to be computed and no double adjustment both of the dial and of the setting hand being required as is the case wherein the ring 83 or its equivalent is adjustably carried by the casing instead of by the setting handle.

In Figs. 26 and 27 I show how several of the parts in Figs. 1 and 2 may be done away with by providing gear 48 with an operating drum 86 concentric with "off" action timer handle 50 and carrying graduations to register with the latter. In this arrangement drum 86 is assumed to connect directly with gear 48 and serve as a substitute for parts 47, 46, 46a and 45. Dial 86a projects from the casing to be adjustable as above mentioned in respect to dial 83 which expedient in the use of dials graduated to represent hours has previously been practiced and enables the setting of the time pointers directly at the time of day the automatic actions are desired to take place if the 45 graduation on the dial representing the present time of day is first turned to register with the starting position of the time pointers at zero which may be indicated by the usual index or other mark represented at 85 in Figs. 24 and 25. 50 This avoids the necessity of computing intervals of time when it is desired to set the device to act at future predetermined times of day.

Fig. 28 shows how a specially marked switch indicator dial 87 may act to indicate not only the position of the switch, whether "on" or "off", but also to tell whether or not the switch is cocked for time-controlled automatic action. It will be noticed from reference to Figs. 5 and 9 that a slight rotative advance of the arms 33 accompanying cocking of the switch. As arms 33 carry the switch-indicator, by providing the latter with two closely adjacent markings, one, only, of those markings may be made to show in the casing window when the switch is not cocked, but both markings to be made visible by the slight rotative advance of arms 33 above referred to. Thus only the word "off" or "on" can be made visible when not under timer control and the additional word "set" may be caused to 70 come into view when the switch is cocked for timer control, thereby to indicate this special condition of the switch.

By adding a duplicate of the timing mechanism and timer levers 14 and 15 on the opposite side 75 of the switch, it will be seen that four automatic

actions of the switch could as well be controlled by one setting of the device.

This double action form of timer mechanism is as easily applicable to effect and time the double action at different pre-determined times of a gas valve or other agent when the latter is provided with automatic actuating means equivalent to the switch-spring 27 of the disclosed embodiment. Thus, the valve shown in my Patent No. 1,385,098, issued July 19, 1921 could be made to both open and close under time control by one setting of the timer under the principles of the present invention.

Thus, in Figs. 29 and 30 it is within the scope of a mechanic's skill to provide a gas cock 90, like the gas cock 12 of my above mentioned patent with operating connection, as for example, the gears 91 and 92 to the rotor 26 whereby spring 27 may cause the actuation of said cock according to the principles of this invention. It would be a convenient expedient to provide cock 90 with a seating in a solid portion 93 of the frame 12 through which gas ports 94 and 95 may be cut off or put in communication by the port 96 in cock 90 by consecutive 90-degree turns of the latter corresponding to the 90-degree positionings of the contact blades 25 in Fig. 1 whereby the flow of gas may be governed between the inlet 97 and outlet 98 threaded to receive piping connection. It will be understood that no invention is herein claimed in the substitution of a gas cock for electric switch contacts 23 and 25 to be controlled by handle 34 through the medium of spring 27 with or without operation of the timing mechanism and that claims directed specifically to the inclusion of a gas cock or device other than electric switches, in combination with the present improvements in timing mechanism are subject matter of applications for United States patent divisional herefrom.

It will be noted in Figs. 29 and 30 that I have shown cam 40 impelled in reduced speed ratio to the rotation of spindle 35 by a set of reduction gears 99, 100, 101 and 102 just as cam 40 of my Patent 1,385,098 is impelled in reduced speed ratio to the spindle 43 by the reduction gears 70, 81, 82 and 42 of said patent; the slow time pointer 103 functioning as does pointer 72 of my issued patent.

I, therefore, do not limit the scope of the invention to the precise mechanisms and construction pictured and described, but what I claim is:

1. In combination, a uni-directional rotary snap switch contactor, a handle movable in advancing stages of progressive travel to tension the said contactor for successive current switching follow up movements relative to said handle, a spring connecting said contactor to said handle to cause said follow up movement, a fixed detent, a cam operated by said handle and co-operating with said fixed detent first to detain said contactor in arrears of said handle and then suddenly to release said contactor for quick spring caused follow up movements relative to said handle responsive to successive advance movements thereof, a catch to hold said handle relatively in advance of said contactor, and a detent operative independently also to detain and release said contactor while tensioned by said spring in arrears of said handle, together with a time determining means operative to control said detent.

2. In a timer, a time-retarded, spring driven rotor, two switch operating members normally urged to a stop-determined position by said rotor,

- two handles connected respectively to said members to remove same from said positions to determine the period of timer action, one of said handles being also connected to wind the rotor spring, 5 and connection between said members permitting their separate manual adjustment to different relative positions, said connection normally holding said members in their manually established relation to cause them to be driven in unison by the clock.
3. In a multiple action timer, in combination, two switch actuating members, a spring driven timing mechanism, a handle for operating one of said members, a separate handle for operating 10 the other of said members and also having connections for winding the spring of the timing mechanism, and a connection between said members rendering them relatively adjustable by said two handles but maintaining them in fixed relation when unobstructed to be driven in unison by the timing mechanism.
4. In combination, a uni-directional rotary snap switch contactor, a handle movable in the same direction to tension the said contactor for current switching movement, a spring connecting said contactor to said handle, a fixed detent for causing snap action of said contactor, a cam operated by said handle in co-operation with said fixed detent to first detain and then suddenly release said contactor for quick spring-caused follow up movements responsive to successive advance movements of said handle, a catch to hold said handle relatively in advance of said contactor and a plurality of time controlled detents operative, to detain and release said contactor while tensioned by said spring and in respectively different positions in arrear of said handle.
5. In combination, a uni-directional rotary snap switch contactor, a handle movable in the same direction to tension the said contactor for current switching movement, a spring connecting said contactor to said handle, a fixed detent for causing snap action of said contactor, a cam operated by said handle in co-operation with said fixed detent to first detain and then suddenly release said contactor for quick spring-caused follow up movements responsive to successive advance movements of said handle, a catch to hold said handle relatively in advance of said contactor and two time controlled detents operative to detain and release said contactor first in circuit breaking position and next in circuit making position while tensioned by said spring.
6. In combination, a uni-directional rotary snap switch contactor, a handle movable in the same direction to tension the said contactor for current switching movement, a spring connecting said contactor to said handle, a fixed detent for causing snap action of said contactor, a cam operated by said handle in co-operation with said fixed detent to first detain and then suddenly release said contactor for quick spring-caused follow up movements responsive to successive advance movements of said handle, a catch to hold said handle relatively in advance of said contactor and a spring driven time mechanism having a common handle to wind the spring thereof and to predetermine its period of action and a detent controlled by said time mechanism and operative to detain and release said contactor while tensioned by said spring in arrear of said handle.
7. In combination, a uni-directional rotary snap switch contactor, a handle movable in the same direction to tension the said contactor for current switching movement, a spring connecting said contactor to said handle, a fixed detent for causing snap action of said contactor, a cam operated by said handle in co-operation with said fixed detent to first detain and then suddenly release said contactor for quick spring-caused follow up movements responsive to successive advance movements of said handle, a catch to hold said handle relatively in advance of said contactor, a time mechanism, and detent means conditioned by said time mechanism to arrest and release said contactor thereby to delay and predetermine the time of the follow up movement of said contactor responsive to said handle.
8. In timing mechanism for an electric switch, common means to operate the switch manually and to condition said switch for automatic action under control of the timing mechanism and indicator means operative to show the position of the switch and also operative to indicate whether said switch is or is not conditioned for control by said mechanism.
9. In an electric switch timer embodying a switch contact member tensionable for quick movements between successive circuit-controlling positions, in combination, a plurality of detents conditionable to hold and to release said member in a plurality of its said positions, a spring driven time mechanism with timers impelled thereby so to condition said detents, and having a common handle both to wind the spring of said mechanism and to position said timers thereby to predetermine the times of their action upon said detents, together with power means operative to advance said switch member through a plurality of its said positions under the control of said detents.
10. In combination with a uni-directional rotatable switch contact, means to tension the same for progressive movements to successive circuit controlling positions, and timer mechanism driven by a spring to control the said contact movements responsive to said means including a time setting handle operable to predetermine the time said mechanism shall be active upon said contact and connected simultaneously to wind the driving spring for said mechanism.
11. In combination with a uni-directional rotatable switch contact, means to tension the same for progressive movements to successive circuit controlling positions, and timer mechanism driven by a spring to control the said contact movements responsive to said means including a time setting handle operable to predetermine the time said mechanism shall be active upon said contact and connected to wind and unwind the driving spring for said mechanism.
12. In combination with a uni-directional rotatable switch contact, means to tension the same for progressive movements to successive circuit controlling positions, and timer mechanism driven by a spring to control the said contact movements responsive to said means including a time setting handle operable to predetermine the time said mechanism shall be active upon said contact and said handle being reversely movable to reduce the time setting after any winding of said spring thereby.
13. In combination with rotary snap switch mechanism comprising an operating shaft, a coaxial contact carrying sleeve rotatable around and relative to said shaft and connected by a spring thereto,—stationary detent means, and

- a sliding member rotatable with said shaft and sleeve and movable radially inward and outward with respect to the axis of said shaft and sleeve by relative rotative movement between said shaft and sleeve, a catch positionable to intercept and free said sleeve for movement, and a time giving mechanism to govern the action of said catch. 5 80
14. In combination with rotary snap switch mechanism comprising an operating shaft, a coaxial contact carrying sleeve rotatable around and relative to said shaft and connected by a spring thereto,—stationary detent means, and a sliding member rotatable with said shaft and sleeve and movable radially inward and outward 10 85
- 15 with respect to the axis of said shaft and sleeve by relative rotative movement between said shaft and sleeve, and time giving mechanism arranged to arrest and free said sleeve for movement independently of said means. 90
16. 15. In a time-controlled snap switch mechanism, a central switch operating shaft, a rotatable contact carrying sleeve surrounding said shaft, a spring in the space between said shaft and sleeve and connecting the two, detent means 15 95
- 25 at one end of said sleeve to cause intermittent spring impelled movements thereof responsive to turning of said shaft, a stop member rotatable with said sleeve at the opposite end thereof and time controlled mechanism operative to arrest 30 and release said stop member. 100
17. In a time-controlled snap switch mechanism, a central switch operating shaft, a rotatable contact carrying sleeve surrounding said shaft, a spring in the space between said shaft and sleeve and connecting the two, detent means 35 105
- 40 at one end of said sleeve to cause intermittent spring impelled movements thereof responsive to turning of said shaft, a stop member rotatable with said sleeve at the opposite end thereof and time controlled mechanism operative to arrest and release said stop member, together with a latch operative to catch and hold said shaft rotatively advanced to tension said sleeve for later time controlled action. 110
18. 17. In a time controlled snap switch mechanism, a central switch operating shaft, a rotatable contact carrying sleeve surrounding said shaft, a spring in the space between said shaft and sleeve and connecting the two, detent means 45 115
- 50 at one end of said sleeve to cause intermittent spring impelled movements thereof responsive to turning of said shaft, a stop member rotatable with said sleeve at the opposite end thereof and a spring driven time movement arranged to 55 cause the arrest and release of said stop member. 120
19. In timer operated switch mechanism, a time giving movement including a power spring, electric circuit controlling contacts, a member connected to operate an electric contact and to 60 125
- 65 be impelled by said movement and to wind said movement spring, another member connected to operate an electric contact, and connection between said members permitting their variable relative adjustment to different rotative timing positions, said connection when undisturbed holding said members in their established rotative relation to cause them to be driven in unison by said movement. 135
- 70 20. In timer operated switch mechanism, a time giving movement including a power spring, electric circuit controlling contacts, a member connected to operate an electric contact and to be impelled by said movement and to wind said movement spring, another member connected to 75 140

- other member connected to operate an electric contact, and connection between said members permitting their variable relative adjustment to different rotative timing positions, said connection when undisturbed holding said members in their established rotative relation to cause them to be driven in unison by said movement. 80
21. In timer operated mechanism, a time giving movement including a power spring, electric circuit controlling contacts, a member connected to operate an electric contact and to be impelled by said movement and to wind said movement spring, another member connected to operate an electric contact, and connection between said members permitting their variable relative adjustment to different rotative positions, said connection when undisturbed holding said members in their established rotative relation and causing said first member to be impelled by the other said member. 100
22. In timer operated switch mechanism, a time giving movement, a power spring, a frictional clutch for slippably coupling said movement and said spring, a spindle connected with said spring for winding the same, electric circuit controlling switch contacts, connection between said spindle and a switch contact whereby the former operates the latter, a contact operating member and a slippable clutch connection causing said member to be impelled by said spindle and also rendering said member rotatably adjustable relative thereto, and means preventing the rotative movement of said member relative to said spindle past a given point. 115
23. In timer operated switch mechanism, a time giving movement, a power spring, a slippable clutch coupling said movement and said spring, a spindle connected with said spring for winding same and having a stop determined zero position, electric circuit controlling switch contacts, connection between said spindle and a switch contact whereby the former causes the latter to break circuit upon arriving at its said zero position, a member connected to be yieldingly impelled by said spindle thereby to permit rotation of said spindle relative thereto when itself arrested, and also having a zero position, and connections whereby said member operates the switch contact to close the circuit upon arriving at its said zero position, so that said member and said spindle may be absolutely and relatively set to cause automatic closing and opening of the circuit at predetermined and respectively different times. 125
24. In timing mechanism in combination, a time giving movement, a power spring for impelling said movement, a spindle connected to turn in one direction to wind said spring and to be impelled by said spring in the opposite direction, an indicator yieldingly connected to said 145
- 150

- spindle to show movement thereof and to permit at times rotation of said spindle independently of and relative to said indicator, and means positively limiting the extent of relative movement between said indicator and said spindle.
25. In timing mechanism in combination, a time giving movement, a power spring for impelling said movement, a spindle connected to turn in one direction to wind said spring and to be impelled by said spring in the opposite direction, an indicator yieldingly connected to said spindle to show movement thereof and to permit at times rotation of said spindle independently of and relative to said indicator, and means positively limiting the extent of relative movement between said indicator and said spindle, together with a stationary stop disposed to limit the absolute movement of said spindle.
26. In timing mechanism in combination, a time giving movement including a power spring, a spindle connected to wind said spring when turned in one direction, a combined indicator and handle for turning said spindle and for indicating the degree of said turning, means whereby said indicator handle positively engages said spindle in direction to wind, a slippable clutch arranged so that said indicator handle may be impelled in the opposite direction by said spindle and manually turned in said opposite direction independently of said spindle, together with a stop preventing more than a full turn of both said spindle and said member.
27. In a device of the character described, the combination of a spring, a clock movement, a frictional connection between them permitting independent movement of the spring, means for winding the spring, means for indicating the degree of said winding, an electrical circuit closing and breaking device, means for operating the
- same to break the circuit connected with said winding means and operable when the same moves to unwound position, a device connected with said winding means but movable independently thereof, a connection between said device and said circuit closing and breaking device whereby the said circuit is closed when the said device is brought to home position, the construction and arrangement being such that the winding device may be moved to unwound position after the said device movably connected therewith has been brought to home position, whereby the circuit may be closed by the latter after a given interval of time and broken by the former after the lapse of an interval of time thereafter.
28. In combination with the mechanism specified in claim 27, a hand operated device for closing and breaking the circuit independently of the other means.
29. The combination of a winding shaft, a spring connected therewith to be wound thereby, a clock movement, a clutch connecting said spring and movement, and permitting independent movement of the former under abnormal stress, an electric circuit closing and breaking device connected with said winding shaft and arranged to be operated thereby, and a member operative to close the said circuit connected with said shaft but movable independently thereof to said circuit closing position, and means for detaining it in such position, a stop on said member and a member fixed to the shaft in the path of said stop.
30. In the mechanism specified in claim 29, the said circuit breaking means connected with the shaft being arranged to operate when the said member on the shaft comes in contact with the stop.
